APPARATUS FOR THE CONTROL OF
HIGHWAY CROSSING SIGNALSHarry C. Vantassel, Swissvale, Pa., assignor to
The Union Switch & Signal Company, Swiss-
vale, Pa., a corporation of Pennsylvania

Application June 25, 1942, Serial No. 448,334

7 Claims. (Cl. 246—130)

My invention relates to apparatus for the control of highway crossing signals, and particularly to apparatus for governing the operation of highway crossing signals when a train receding from the intersection, reverses its movement and approaches the intersection.

A railway track which intersects a highway at grade is usually formed with control track sections on each side of the intersections and train movements in such sections govern highway crossing signals located at the intersection. Directional means is provided in the control apparatus to avoid operation of the highway crossing signals when a train recedes from the intersection. Such control apparatus as heretofore provided does not ordinarily operate the signal if a train reverses its receding movement and approaches the intersection with the result that highway users may receive no warning of such approaching train.

A feature of my invention is the provision of novel and improved control apparatus for highway crossing signals for operating the signals when a train reverses its receding movement and approaches the intersection.

Other features and advantages of my invention will appear as the specification progresses.

I shall describe one form of apparatus embodying my invention, and shall then point out the novel features thereof in claims.

The accompanying drawing is a diagrammatic view showing one form of apparatus embodying my invention.

Referring to the drawing, the reference characters $1a$ and $1b$ designate the track rails of a railway track over which traffic moves in either direction, and which track is intersected at grade by a highway H , a highway crossing signal S being located at the intersection. Signal S may be an audible signal, a visual signal, a gate, a barrier or a combination of such devices as desired, and for simplicity signal S is disclosed as an audible signal in the form of an electric bell.

The track rails $1a$ and $1b$ are formed by the usual insulated rail joints, with three track sections AT , BT and CT , the intermediate section BT including the intersection with the highway H and preferably extending only a short distance to each side of the highway. Sections AT and CT are control sections extending to the left and right, respectively, of the intersection, and each section AT and CT is of a length sufficient to assure a predetermined warning period of signal S prior to the arrival of a train at the intersection when such train approaches the inter-

section at the maximum permissible speed. Sections AT , BT and CT are each provided with a track circuit including a current source, such as a battery 2 connected across the rails at one end of the section and a track relay R with a prefix corresponding to the section connected across the rails at the other end of the section.

According to my invention, two track instruments XA and XC are provided, track instrument XA being located at a preselected point along section AT and track instrument XC being located at a preselected point along section CT . These track instruments XA and XC are of the directional type, and their construction may be any one of several well-known arrangements wherewith a contact is actuated only when a train passes over the track instrument in a given direction, and such contact is not actuated by a train moving in the opposite direction. Track instruments XA and XC are shown conventionally since their specific construction forms no part of my invention, and it is sufficient for the present application to point out that track instrument XA is located adjacent a rail at a preselected point along section AT , and is disposed for its normally closed contact 3 to be actuated to an open position only when an eastbound train, that is, a train moving from left to right as viewed in the drawing, passes over the track instrument, but that contact 3 remains closed when a westbound train, that is, a train moving from right to left as viewed in the drawing, passes over the track instrument. Similarly, track instrument XC is located adjacent a rail at a preselected point along section CT and is disposed for its normally closed contact 4 to be actuated to an open position only when a westbound train passes over the track instrument, but that contact 4 remains closed when an eastbound train passes this instrument. That is to say, each track instrument XA and XC is disposed to be actuated only by trains approaching the intersection. An arrow is placed adjacent each track instrument XA and XC to indicate the direction in which a train must move over the track instrument to actuate its contact.

The track relays of the track sections and the two track instruments XA and XC govern the operation of signal S through the medium of a control relay XR and two directional means, one of which includes an interlocking relay IR and the other of which includes two stick relays ASR and CSR , relay ASR being associated with east-

bound traffic, and relay CSR being associated with westbound traffic.

Normally, that is, when the track sections are unoccupied and the respective track relays are picked up, both magnets ATP and CTP of interlocking relay IR, both stick relays ASR and CSR and control relay XR are energized and the signal S is silent. Under such normal condition the magnet ATP of relay IR receives current from terminal B of any suitable source of current, such as a battery not shown, through front contacts 5 and 6 of track relays ATR and BTR, respectively, and winding of magnet ATP to terminal C; and the other magnet CTP of the interlocking relay receives current from terminal B through front contacts 7 and 8 of track relays CTR and BTR, respectively, and winding of magnet CTP to terminal C. Directional stick relay ASR normally receives current through its pick-up and stick circuits in multiple, the pick-up circuit including terminal B, normally closed contact 3 of track instrument XA, front contact 9 of magnet ATP of the interlocking relay and winding of relay ASR to terminal C; and the stick circuit being the same as the pick-up circuit except it is completed around front contact 9 of magnet ATP through front contact 10 of relay ASR. Similarly, directional stick relay CSR normally receives current through its pick-up and stick circuits in multiple, its pick-up circuit extending from terminal B through contact 4 of track instrument XC, front contact 11 of magnet CTP of the interlocking relay and winding of relay CSR to terminal C; and its stick circuit being the same as its pick-up circuit except it by-passes the front contact 11 of magnet CTP through front contact 12 of relay CSR. Control relay XR is normally energized by current supplied from terminal B through flagman contacts 13 and 14 of magnets ATP and CTP, respectively, of the interlocking relay, front contacts 15 and 16 of stick relays ASR and CSR, respectively, and winding of relay XR to terminal C. Relay XR controls at its back contact 17 an obvious operating circuit for signal S and it is clear that signal S is normally silent but is operated to sound a warning whenever relay XR is released.

Assuming that an eastbound train approaches the intersection to enter section AT and shunt track relay ATR to open its front contact 5, the magnet ATP of interlocking relay IR is deenergized and releases to its full down position where both flagman contact 13 and front contact 9 are open. The opening of flagman contact 13 opens the circuit for control relay XR and that relay is deenergized and released to close its back contact 17 so that signal S is operated to sound a warning. The opening of front contact 9 of magnet ATP opens the pick-up circuit for stick relay ASR but relay ASR is retained energized by its stick circuit. When this eastbound train has advanced in section AT far enough for its leading vehicle to reach the location of track instrument XA, the track instrument XA is actuated to open contact 3 and stick relay ASR is deenergized and releases to open its front contacts 10 and 15 and to close its back contact 18. The opening of front contact 15 opens the circuit for the control relay XR at a second point. The closing of back contact 18 completed an alternative circuit for magnet ATP and current flows from terminal B through back contact 18 of relay ASR, back contact 19 of track relay ATR, front contact 6 of track relay BTR and winding of magnet ATP to terminal C. so that magnet ATP is reenergized

and picked up to close its flagman contact 13 and front contact 9. The closing of flagman contact 13 closes one point in the circuit for control relay XR, but relay XR remains deenergized due to front contact 15 of relay ASR being open and consequently operation of signal S is not interrupted. The closing of front contact 9 of magnet ATP closes one point in the pick-up circuit of relay ASR, but relay ASR receives no current because contact 3 of track instrument XA remains open as long as the train is passing over it.

Assuming that this eastbound train is relatively short and the rear of the train passes beyond track instrument XA allowing contact 3 to close before the leading vehicle of the train enters section BT, stick relay ASR is picked up over its pick-up circuit. The picking up of relay ASR to open back contact 18 deenergizes magnet ATP, and that magnet is again released to its full down position where both contacts 9 and 13 are open, stick relay ASR being now retained energized through its stick circuit. The control relay XR would be momentarily energized between the picking up of relay ASR and the release of magnet ATP because magnet ATP is preferably made slightly slow to release. However, control relay XR is provided with a slow pick-up period sufficiently long that relay XR is not picked up before magnet ATP is released and hence there is no interruption in the operation of signal S. When this eastbound train enters section BT to shunt track relay BTR, that relay is released to open both front contacts 6 and 8. The opening of front contact 6 of relay BTR opens the circuit for magnet ATP at a second point, magnet ATP having previously been released in the manner described above. The opening of front contact 8 of track relay BTR opens the circuit for the second magnet CTP of the interlocking relay and magnet CTP is deenergized and released to the interlocked position where its front contact 11 is open but its flagman contact 14 remains closed. The opening of front contact 11 of magnet CTP opens the pick-up circuit for stick relay CSR but relay CSR is retained energized over its stick circuit. When this eastbound train enters section CT in receding from the intersection, the track relay CTR is shunted and releases to open at its front contact 7 the circuit for magnet CTP at a second point. When the rear of this eastbound train vacates section AT, track relay ATR is reenergized and picked up and when this train passes beyond the intersection and vacates section BT track relay BTR is reenergized and picked up to close the circuit for magnet ATP and that magnet is energized and picked up to close its contacts 13 and 9. With the closing of flagman contact 13 of magnet ATP, the circuit for control relay XR is closed and that relay is energized and picked up to discontinue the operation of signal S. This eastbound train passes track instrument XC without actuating the instrument and hence stick relay CSR remains closed as the train recedes from the intersection. When this train vacates section CT track relay CTR and in turn magnet CTP are reenergized.

Should this eastbound train while receding from the intersection through section CT and after some portion of the train at least has moved beyond track instrument XC, stop and reverse its movement to approach the intersection, the track instrument XC is actuated by the train to open contact 4 and deenergize stick relay CSR and relay CSR upon releasing to open front con-

tact 16 deenergizes the control relay XR and that relay releases to cause operation of signal S. With relay CSR released magnet CTP receives current through its alternative circuit including back contact 20 of relay CSR and back contact 21 of track relay CTR, with the result that magnet CTP is energized and picked up, the interlocking feature of relay IR being released because both magnets ATP and CTP are now picked up. Operation of signal S is continued, however, due to relay CSR being released. When this train moves to the west toward the intersection far enough to pass off track instrument XC, contact 4 is closed and relay CSR is reenergized through its pick-up circuit. The pick-up of relay CSR closes the circuit for relay XR at front contact 16, and opens the alternative circuit for magnet CTP at back contact 20. Magnet CTP is now deenergized and releases to its full down position to open the circuit for relay XR at flagman contact 14. Although relay XR receives energy during the slow release period of magnet CTP, the slow pick-up period of relay XR is sufficient to prevent its picking up before magnet CTP is released and operation of signal S is continued without interruption. With magnet CTP of relay IR released to its full down position, the operation of signal S is continued until this eastbound train that has reversed its movement in section CT, passes to the west beyond the intersection to vacate section BT. Furthermore, magnet ATP is held at the interlocked position and operation of signal S is discontinued if this train continues its westward movement through section AT.

Assuming that the apparatus is in its normal condition and a relatively long eastbound train approaches the intersection, the operation of the apparatus is the same as previously described up to the point where the track instrument XA is actuated to open contact 3 and deenergize stick relay ASR to close its back contact 18 so that magnet ATP is reenergized and picked up. The head end of this relatively long eastbound train will enter section BT and shunt track relay BTR before the rear of the train has passed track instrument XA to permit contact 3 to reclose and reenergize relay ASR to in turn deenergize magnet ATP. Thus relay BTR is released by this train at a time both magnets ATP and CTP of the interlocking relay are picked up, and the two magnets are simultaneously deenergized and released. The interlocking feature of relay IR is arranged so that when both its magnets are simultaneously released, the armature of each magnet drops only to the interlocked position wherein flagman contacts 13 and 14 are retained closed but front contacts 9 and 11 are open. Hence stick relay ASR is not at once reenergized and picked up when the rear of this relatively long eastbound train passes beyond track instrument XA, and with relay ASR released control relay XR remains deenergized causing operation of signal S. When this train vacates section AT and then section BT so that both track relays ATR and BTR are picked up, magnet ATP is reenergized to close front contact 9 with the result that stick relay ASR is then reenergized and picked up. The circuit of control relay XR is now closed and thus operation of the signal S is discontinued when this relatively long train passes beyond the intersection and vacates section BT. If this train stops in the section CT and reverses its movement to approach the intersection, the track instrument XC is actuated to open contact

4 and deenergize stick relay CSR to cause operation of the signal in the manner explained hereinbefore.

In the event an eastbound train enters section 5 AT to initiate operation of signal S, advances far enough in section AT to actuate track instrument XA to release stick relay ASR and then stops with track instrument XA between the truck wheels of a car of the train, the contact 3 of track 10 instrument XA would close and relay ASR would be reenergized over its pick-up circuit. With relay ASR picked up, magnet ATP would be deenergized and released due to the opening of back contact 18 of relay ASR, and consequently relay 15 XR would remain released to continue the operation of signal S.

It is apparent from the foregoing description of the operation of the apparatus for eastbound 20 trains, together with an inspection of the drawing, that the apparatus will operate in a similar manner for westbound trains.

The apparatus here disclosed has the advantages that operation of a highway crossing signal when a receding train reverses its movement is 25 accomplished with relatively simple and inexpensive means and added track sections with expensive subsection equipment for operating the signal are avoided.

Although I have herein shown and described 30 but one form of apparatus for the control of highway crossing signals embodying my invention, it is understood that various changes and modifications may be made therein within the scope of the appended claims without departing 35 from the spirit and scope of my invention.

Having thus described my invention, what I claim is:

1. In combination with a highway crossing signal located at the intersection of a highway and 40 a railway track, a track section disposed to one side of the intersection and provided with a track circuit including a track relay, operating means controlled by said track relay to operate the signal when a train occupies the section, 45 train governed means controlled by a train approaching the intersection on the side opposite that of said track section to operate said signal and to remove said track relay from control of 50 said operating means as this train occupies said section in receding from the intersection, a directional train actuated means located at a preselected point within said section and actuated only by a train moving in the direction to approach the intersection, and means governed by 55 said directional train actuated means to control said operating means to operate said signal independent of said track relay.

2. In combination with a highway crossing signal located at the intersection of a highway and 60 a railway track, a track section disposed to one side of the intersection and provided with a track circuit including a track relay, operating means controlled by said track relay to operate the signal when a train occupies the section, train governed means controlled by a train approaching the intersection on the side opposite that of said track section to operate said signal and to remove said track relay from control of said operating means as this train occupies said section in receding from the intersection, a track instrument located at a preselected point along said section and having a contact which is actuated only by a train moving in the direction to approach said intersection, and circuit means in-

cluding said contact to control said operating means to operate said signal.

3. In combination with a highway crossing signal located at the intersection of a highway and a railway track, a track section disposed to one side of the intersection and provided with a track circuit including a track relay, another relay, a stick relay, a directional train actuated device located at a preselected point along said section and having a contact which is actuated only by a train moving in the direction to approach the intersection, a first circuit including a front contact of said track relay to energize said other relay, a second circuit including a back contact of said track relay and a back contact of said stick relay to energize said stick relay, a stick circuit to energize said stick relay and including said contact of the train actuated device, operating means controlled by said other relay and said stick relay to operate said signal when either said other relay or said stick relay is released, and directional means governed by a train approaching the intersection on the side opposite said track section to operate said signal and to remove said other relay from control of said operating means as this train recedes from the intersection.

4. In combination with a highway crossing signal located at the intersection of a highway and a railway track, a track section disposed to one side of the intersection and provided with a track circuit including a track relay, another relay, a stick relay, a directional train actuated device located at a preselected point along said section and having a contact which is actuated only by a train moving in the direction to approach the intersection, a first circuit including a front contact of said track relay to energize said other relay, a second circuit including a back contact of said track relay and a back contact of said stick relay to energize said stick relay, a stick circuit to energize said stick relay and including said contact of the train actuated device, a control relay, a control circuit including in series a front contact of said other relay and a front contact of said stick relay to energize said control relay, an operating circuit including a back contact of said control relay to operate said signal, and directional means governed by a train approaching the intersection on the side opposite said track section to operate said signal and to remove said other relay from control of said control relay as this train recedes from the intersection.

5. In combination with a highway crossing signal located at the intersection of a highway and a railway track, two track sections extending in opposite directions from the intersection and each provided with a track circuit including a track relay, directional relay means controlled by said track relays to operate said signal when a train occupies either one of said sections in approaching the intersection and to discontinue

such operation when the train occupies either section in receding from the intersection, two directional track instruments one located at a preselected point within each of said sections, and means controlled by each of said directional track instruments to operate said signal independent of said directional relay means for operating the signal when a receding train reverses its movement and approaches the intersection.

6. In combination with a highway crossing signal located at the intersection of a highway and a railway track, two track sections extending in opposite directions from the intersection and each provided with a track circuit including a track relay, directional relay means controlled by said track relays to operate said signal when a train occupies either one of said sections in approaching the intersection and to discontinue such operation when the train occupies either section in receding from the intersection, two directional track instruments one located at a preselected point along one of said track sections and the other located at a preselected point along the other one of said track sections, each of said track instruments provided with a normally closed contact and disposed to be actuated to open its contacts only by a train approaching the intersection, a directional stick relay for each said track instrument, each said stick relay provided with a pick-up circuit including a contact of the associated instrument and a contact controlled by the track relay of the associated track section and with a stick circuit including a contact of the associated instrument, and means controlled by each of said stick relays to operate said signal when such stick relay is released.

7. In combination with a highway crossing signal located at the intersection of a highway and a railway track, two track sections extending in opposite directions from the intersection and each provided with a track circuit including a track relay, an interlocking relay having one of its magnets energized through a front contact of one of said track relays and its other magnet energized through a front contact of the other one of said track relays, two directional track instruments one located along one of said track sections and the other located along the other one of said track sections, each said track instrument disposed to be actuated to open its normally closed contact only by a train approaching the intersection, a directional stick relay for each said track instruments, each said stick relay provided with a pick-up circuit including the contact of the associated instrument and a front contact of the interlocking relay magnet associated with the same section and with a stick circuit including the contact of the associated instrument, an alternative circuit for each of said magnets and including in series a back contact of the respective track relay and a back contact of the associated stick relay, a control relay energized by a circuit including in series a flagman contact of each of said interlocking relay magnets and a front contact of each of said stick relays, and an operating circuit controlled by said control relay to operate said signal.
